UNITED STATES PATENT OFFICE.

JAMES EDWARD SMITH, OF NEW YORK, N. Y.

CIGAR-BUNCHING MACHINE.

SPECIFICATION forming part of Letters Patent No. 738,636, dated September 8, 1903.

Application filed November 11, 1902. Serial No. 130,929. (No model.)

To all whom it may concern:

Be it known that I, JAMES EDWARD SMITH, a citizen of the United States, and a resident of the city of New York, borough of Manhattan, in the State of New York, have invented certain new and useful Improvements in Cigar-Bunching Machines, of which the following is a full, clear, and exact specification.

The present invention relates to improvements in cigar-bunching machines, examples of which are disclosed by prior Letters Patent of the United States issued to me October 30, 1888, No. 392,076; February 5, 1889, No. 397,396; April 9, 1889, No. 401,077; April 23, 1889, Nos. 402,038 and 402,039, and on June 18, 1889, No. 405,439.

In my prior Letters Patent of the United States No. 393,727 for blanks for cigar-filters and No. 393,726 for method of making cigar-bunches, both dated November 27, 1888, I have disclosed a way of preparing leaf-tobacco for manufacturing long-filler cigars, cigarettes, and cheroots. As therein set forth, the bunch for a cigar, cigarette, or cheroot, has a long filler of leaf-tobacco extending continuously throughout the length thereof, and this bunch is made of the desired or any preferred shape by cutting the leaf in the shape of the cigar which it is desired to produce, after which the prepared filler is rolled upon itself to produce the bunch of the desired contour and size, the binder is rolled, and the bunch should finally be wrapped to complete the product. The substantial advance secured in the art by these contributions thereto resides in the production of long-filler cigars rapidly and economically, each of which is free from compression of the tobacco or condensation of the bunch, has the desired longitudinal and cross-sectional shape, and which will draw easily and regularly, or, in other words, the air and smoke can pass freely through the filler and the cigar will not burn more rapidly on one side than on the other.

My chief object in the present invention is to produce a machine for manufacturing soft long-filler cigar-bunches of any desired or preferred shape both rapidly and cheaply.

The machine, to be hereinafter described, has all of its mechanisms and parts combined for automatic operation to continuously carry

on the work of feeding long-filler leaf-tobacco to a cutter mechanism by which the tobacco is cut at regular intervals into fillers of any desired or preferred shape, and thereafter the shaped filler of long-leaf tobacco is delivered to a binder-rolling mechanism which automatically applies the binder and discharges a completed bunch from the machine.

One of the peculiar and essential parts of the machine is a filler-forming mechanism including an endless traveling trough consisting of jointed links each having a self-opening side adapted to permit of the ready introduction of a long-filler leaf of tobacco sideways into the endless trough, whereby a number of long tobacco-leaves may be introduced by practically unskilled labor. In coöperative relation to the trough is a gage disposed, preferably, in overhanging relation to the space of the trough at the open side thereof, through which the long filler is adapted to be introduced. This gage determines or regulates the thickness of the filler or the diameter of the completed bunch.

Another essential feature of the improved machine resides in the filler-cutting mechanism, which consists of a die-box through which the filler is fed by the filler-forming mechanism, a cutter to give the desired shape to the head end of the filler, and another cutter to impart the proper shape to the tuck end of the filler, said head and tuck cutters having the proper contours and being interchangeable in a moment's time with other cutters of various different shapes in order to produce fillers and bunches of any character demanded by the trade.

Another element of the improved machine resides in a filler-discharging device comprising a receptacle disposed in a position to receive the cut filler from the die-box and a plunger operable in said receptacle, the latter being provided with a normally closed bottom arranged to be opened on the descent of the plunger which serves to carry the filler from said receptacle to the binder-rolling devices. This plunger and the cutter devices are intermittently actuated by operative connections with a double cam on a suitable shaft. The cam has one of its members arranged to drive the vertically-movable plunger twice to every movement of the cutter de-

vices, because it is only necessary to actuate the latter once to every two movements of the plunger, owing to the peculiar action of the cutter devices, while the remaining member of said double cam imparts movement to the cutter devices alternately with respect to the strokes of the plunger, the downward movement of the cutter devices taking place simultaneously with every other downward movement of the plunger.

Another important mechanism in my machine is a feed-motion to intermittently move the endless filler-trough for variable distances at the alternate periods of feed, said filler-trough being capable of a comparatively extended period of movement at one time and of a shorter period of movement at the next time, such periods of long and short movements of the filler-forming trough being repeated automatically in proper sequence and working in harmony with the effective strokes of the double cutter devices in order that fresh filler in proper lengths may be brought into position for action thereon by the cutter devices. This feed-motion embodies an alternating ratchet mechanism comprising an intermittently-driven shaft arranged to impel the endless filler-trough and carrying a single ratchet, a shiftable pawl-lifter normally held in a given position with relation to the ratchet by a retractor device, a pawl-carrier movable on the shaft as its center of motion and carrying a pawl arranged to engage the ratchet, an eccentric linked to the pawl-carrier and arranged to actuate the latter and the pawl in a manner to make the pawl impel the ratchet and the shaft a distance equivalent to the long feed-motion of the endless filler-trough, a cam rotating at less speed than the ratchet, and trip devices actuated at proper periods by the cam and connected with the pawl-lifter to throw the latter into engagement with the pawl, whereby the pawl is held inactive for a short period during a part of the turn of the pawl-carrier under the motion of the eccentric, so that the pawl will not act for so long a period on the ratchet as in the first instance, in consequence of which the ratchet and the shaft will be turned a less angular distance and the desired short feed-motion will be given to the filler-trough. As a result of the one-period movement of the cutter devices to the two periods of movement of the plunger and of the alternating long and short periods of intermittent feed of the filler-trough I am able to cut bunches of long filler without waste each of the same length and emerging from the machine in reversed order—that is to say, the head and tuck ends of one bunch will occupy a reversed order to the tuck and head of the next bunch. By producing bunches of filler in alternating or reversed order one becomes what is technically known as a "right-hand" bunch, which must be wrapped (if the wrapping is performed manually) by applying and rolling the wrapper under the right hand,

while the next bunch is what is known as a "left-hand" bunch, which must be wrapped (if done by hand) by rolling it in a wrapper under the left hand, such designations of "right" and "left" hand wrapping being well understood by those skilled in the art.

The invention further consists in the construction, arrangement, and combination of parts and in the organization of mechanisms which will be hereinafter more fully described, and the actual scope of the invention will be defined by the annexed claims.

Reference is to be had to the accompanying drawings, forming a part of this specification, in which similar characters of reference indicate like parts in each of the several figures.

Fig. 1 is a side elevation of a machine for making long-filler soft cigar-bunches. Fig. 2 is a top plan view of the machine. Fig. 3 is an elevation looking at the left-hand end of the machine shown by Figs. 1 and 2. Fig. 4 is an enlarged vertical sectional elevation through the die-box and the cutters forming the filler-cutting mechanism, showing the delivery portion of the endless filler-trough and one of the filler-tucking wheels. Fig. 5 is a plan view, on a reduced scale as compared with Fig. 4, of the die-box. Fig. 6 is an elevation looking at the rear portion of the die-box shown by Fig. 5. Fig. 7 is an inverted or bottom plan view of a portion of the filler-trough. Fig. 8 is a side elevation of a portion of the filler-trough. Fig. 9 is a cross-section on the line 9-9 of Fig. 10 through the filler-trough. Fig. 10 is a top plan view of the filler-trough. Fig. 11 is an elevation looking at one side of the alternating ratchet devices forming the feed-motion for the filler-trough. Fig. 12 is a sectional elevation of a part of the alternating ratchet, illustrating the normal position of the pawl-lifter and the pawl to effect a partial rotation of the ratchet and the intermittently-driven shaft. Fig. 13 is a sectional elevation similar to Fig. 12, but showing the pawl-lifter in an active position to hold the pawl free from engagement with the ratchet for a limited period in order to effect the short period of advancing movement to the filler-trough. Fig. 14 is a detail plan view of the cam and a part of its shaft, the same adapted to actuate the trip devices of the alternating ratchet mechanism.

In the practical embodiment of my invention in a cigar-bunching machine the several mechanisms are mounted on a suitably-constructed framework, (indicated in its entirety at A in Figs. 1, 2, and 3.) The upper portion of this framework carries a horizontal table B of any appropriate shape and dimensions and arranged at an elevation to suit the convenience of an operator, who is stationed alongside of the machine for the purpose of placing long leaves of tobacco in a filler-forming mechanism. This table B is provided with a tobacco-receptacle b, in which is deposited a suitable quantity of leaf-tobacco, the same having been prepared in a way to

adapt the same for manufacture into cigars—as, for example, by moistening the tobacco. At one end of the table the framework is provided with horizontal shaft-bearings, one of which is indicated at 5, and in these bearings is journaled a horizontal shaft 6, adapted to serve as the means for advancing the endless trough which constitutes the filler-forming mechanism of the machine. The end of the shaft 6 near the front edge of the table is provided with a sprocket-wheel 7, arranged in a position to support an end portion of the endless trough, the latter being indicated in its entirety at C. The other end portion of this trough passes around and is supported by an idler sprocket-wheel, (not shown,) and this trough is arranged to travel or work in a longitudinal slot or opening, the position of which is indicated at d in Fig. 2, said slot having an inclined or curved surface at d', adapted to automatically close the filler-trough, as will hereinafter appear. The filler-driving shaft 6 is intermittently actuated by the alternating ratchet devices in a manner to advance the endless filler-trough with alternately long and short periods of movement, and this filler-trough travels around the driving sprocket-wheel 7 in a manner to deliver the filler of long-leaf tobacco to the die-box D of the cutter devices.

One of the important features of my filler-forming mechanism is the sectional construction of the same and the provision of hinged or pivoted sides arranged to be opened and closed automatically as the members of the filler-trough move along the table and beyond the latter. This filler-trough consists of links 8 9, pivoted end to end to form two chains, which are arranged side by side in parallel relation, as indicated by Figs. 7, 9, and 10. These chains are adapted to be connected by transverse pivotal rods 10, which pivot the links thereof in series, and said rods work or fit in the notches of the sprocket-wheels, as will be readily understood. The chains carry the plurality of members c which form the endless trough, and each member is provided with a movable side c', which is hinged or pivoted at c² to the side c. (See Fig. 9.) The permanent side c of each trough member is secured at c³ to the companion links of the chains, and thus the pairs of links are adapted to carry the endless series of trough members, which are adapted to travel with the links around the sprocket-wheels, as shown by Fig. 4, while the trough members in the horizontal upper and lower parts of the endless trough will lie close together in a manner for the upper lead of the trough to present a pocket or receptacle in which the filler-tobacco can be easily arranged by the hands of the operator. The slot d in the table is wide enough for the members of the trough to open fully as the upper lead of the endless trough travels along the table, and the sides c' of this trough open of themselves as they pass

upwardly around the idler-sprocket, so that the upper edges of the sides c' will move along the table flush therewith during the time that the trough members are in positions to receive the tobacco filler. As the members of the trough approach the inclined or cam surface d' of the table the hinged sides c' ride against this curved surface and are automatically and positively closed thereby.

The die-box D is supported in a stationary position on the framework A to lie substantially in the horizontal plane of the upper lead of the endless filler-trough and substantially in line therewith, whereby the filler from the endless trough is adapted to be discharged directly into the die-box as the trough passes around the sprocket-wheel 7, as indicated by Fig. 4. This die-box D has a bottom section d² and a top plate d³, said bottom section being peculiarly formed to produce the sides d⁴ of the box. The bottom section d² of the box and the sides d⁴ are internally shaped to make the box assume the contour shown by Fig. 6, and these sides d⁴ are cut away at their front edges, as indicated at 11 in Fig. 4, while the rear end portions of the sides d⁴ are curved, as indicated at 12, and thereby constitute cutting edges which are adapted to coöperate with the head-cutter of the cutter devices in order to act with a draw or shear cut. The bottom d² of the die-box is made narrow and tapering at its front end to produce a tongue 13, which is curved upwardly and rearwardly, as shown by Fig. 4, and projects into the pocket or space of the filler-trough at the place where it passes around the sprocket-wheel, as shown, whereby the tongue 13 is adapted to serve as a pick-up in taking the tobacco filler from the trough and directing the same into the lower portion d² of the die-box. The bottom of the die-box is tapered to a point approximately the shape of a letter V, this rear end portion of the bottom corresponding in shape to the rear end portion of the top plate d³, which is shown more particularly by Fig. 5. This top plate d³ is secured by screws or other fastenings to the sides of the die-box, and in this plate d³ is formed a V-shaped slot 14, while the rear end of the plate has a V shape, as shown clearly by Fig. 5. Although I have described the slot 14 as being V-shaped and the end 15 of the plate as being likewise shaped it will be understood that these parts may be of any desired configuration to form the tuck and head of a cigar-bunch, as will presently appear. The bottom d² of the die-box is provided with a V-shaped slot 16, a portion of which is indicated in Fig. 4, said slot 16 corresponding in shape to the slot 14 and disposed in alignment or registration therewith. The tapered rear end of the top plate d³ is inclined downwardly at a slight angle toward the tapered rear end portion of the bottom d², as shown by Figs. 4 and 6, thus preventing the filler or embryo bunch

from rising as it leaves the die-box and after having been cut to the desired shape by the action of the cutter devices.

17 designates a vertically - movable bar 5 which is disposed in a vertical position and is fitted slidably in a guideway 18 on the upper front portion of the framework. This slide or bar is disposed immediately over the die-box D, and to the lower end of the slide is 10 firmly secured a cross-head 19. (See Figs 1 and 4.) This cross-head carries the head-cutter E and the tuck-cutter F, the same being shown by full lines in Figs. 1 and 4 and the shape of which is indicated by dotted 15 lines in Fig. 5. These cutters are provided at their upper ends with the plates e, which are fitted against the bottom side of the cross-head 19 and are secured firmly and detachably thereto by the screws f f', thus making 20 provision for the ready removal of cutters of one shape and the substitution of other cutters having different shapes. The head cutter or knife E consists of two sides disposed at an angle to each other and having the 25 length and shape to cut the filler according to the shape of the head of the cigar which it is desired to produce. The tuck cutter or knife F has two sides disposed at an angle to each other to produce a tuck of the desired 30 shape in the filler or embryo bunch; but I prefer to make the sides of the tuck-knife F at a greater angle than the sides of the head-knife E, as will be seen by reference to Fig. 5. The tuck-knife F is provided at its lower 35 portion with cutting edges, and this knife is carried by the cross-head in a position to work in the alined slots 14 16 of the die-box. In a similar way the head-knife E is provided with cutting edges at its lower portion, and 40 this knife is arranged to work past the edges of the tapered top and bottom portions of the die-box and with the curved side portions 12, whereby said knife E operates snugly against the rear portion of the die-box to cleanly cut the filler with a draw or 45 shear cut.

The slide or bar 17 and the knives or cutters are actuated by a lever 20, arranged in a substantially horizontal position in the upper 50 part of the framework. (See Figs. 2 and 3.) This lever is hung or fulcrumed at one end, as at 21, on the framework, and the other end of the lever is connected pivotally at 22 to the slide 17. (See Fig. 2.) At a point intermediate of its length this lever 20 is equipped 55 with a friction-roller 23, (see dotted lines in Figs. 2 and 3,) arranged to travel in a cam-groove 24 of a double cam 25, the latter being rigidly secured to the upper portion of a vertical 60 shaft 26, which is mounted in vertical alined bearings provided in an end portion of the framework A. The lower end of this shaft is equipped with a bevel gear-pinion 27, which meshes with a similar bevel gear-wheel 28, the latter being rigidly secured to a horizontal counter-shaft 29, that is journaled in suitable horizontal bearings at the lower 65

portion of the framework. This counter-shaft is provided with a large spur-gear 30, arranged to mesh with a spur gear-pinion 31, which is 70 made fast with a sleeve 33, loose on a horizontal driving-shaft 32, the latter being journaled in appropriate bearings of the framework and disposed in parallel relation to the counter-shaft. (See Fig. 3.) This driving 75 or main shaft 32 is provided at one end with a belt-wheel 34, adapted to be driven by a belt (not shown) from any suitable source of power, and said shaft 32 is provided with a clutch member 35, which is keyed to the main 80 shaft in order to rotate therewith and to be capable of a slidable movement thereon under the movement of a shipper-lever 36, the latter being hung on the framework A, suitably connected to the clutch-section and pivoted to a treadle-lever 37, whereby the operator may throw the machine into and out of operation. The sleeve 33, which is loosely mounted on the main shaft and carries the spur-pinion 31, is provided with a clutch-face 85 38, adapted to be engaged by the slidable clutch member 35, and this sleeve serves to drive the vertical shaft and the double cam through the described train of gearing and to also drive the shafts that operate the alternating ratchet for the filler-forming mechanism. The double cam 25 is provided with another cam-groove 39, having two high points, whereas the cam-groove 24 is provided with only one high point, and the two high points 90 in the groove 39 with the one high point of the groove 24 makes the three active portions of this cam. The high point of the cam-groove 24 is disposed coincident with one of the high points in the cam-groove 39, and thus the 95 cutter devices are actuated simultaneously with the plunger 40 at one of the strokes thereof. This plunger 40 is one of the elements of the filler-discharging devices, and it is disposed in a vertical position alongside of the slide 100 17 (see Fig. 1) for movement in a vertical path and parallel to the slide. This plunger is arranged to slide in a guideway 41, which is provided in the upper front portion of the framework, and to the rear side of the plunger 105 is pivoted, at 42, the front end of a lever 43, the latter being hung at a point intermediate of its length, at 44, on the framework. This lever is provided with a rearwardly-extending short arm 45, on which is fitted a 110 shiftable counterweight 46, that is held at a desired point of adjustment by a set-screw 47, whereby the lever is counterweighted in a manner to impart a quick upward movement to the plunger each time the high point of the 115 cam-groove 39 clears a friction-roller 48, that is loosely mounted on the lever 43 at a point to one side of the fulcrum 44. This roller 48 is represented by dotted lines in Figs. 2 and 3, and it travels in the cam-groove 39 of the 120 double cam to be acted on by the two high parts thereof. The lower end face of the plunger 40 is provided with a curved groove or recess 49, (see Fig. 3,) and this grooved end of 125 130

the plunger is arranged to play in a receptacle 50, the latter being firmly secured in a horizontal position on the framework. This receptacle 50 is arranged in alignment with the die-box D, as shown by Fig. 1, in order that the rear delivery end of the die-box may open directly into the receptacle, and thus the cut filler or embryo bunch is adapted to be discharged from the die-box into the receptacle at proper intervals and into the path of the recessed end of the plunger. The bottom portion of the receptacle 50 is normally closed by the flap or flaps 51, two of which are preferably employed, as shown by Fig. 3. These flaps or doors are hinged individually at 52 to the opposite sides of the receptacle, and these flaps or doors may be kept in closed aligned positions by springs, such as 53, or their equivalents. (See Fig. 1.)

The mechanism for applying the binder to the filler after the latter is delivered from the receptacle 50 is indicated more clearly by Figs. 1, 2, and 3, in which a rolling-table is indicated at 54, the latter being rigidly secured to the framework to extend outwardly therefrom and to assume a horizontal position in the path of the plunger. This rolling-table is provided with a raised portion 55, across which extends an apron 56, one end of which is secured between the table and its raised portion, while the other end is fastened to the framework, as shown more clearly by Fig. 3. This apron has a certain allowance of slack, and it is traversed by a roller 57, which is arranged to ride against the lower side of the apron in a manner to form therein a pocket adapted to receive the bunch from the receptacle and the plunger. (See Fig. 3.) The roller 57 is idly mounted in a pair of plates 58, which are fastened to opposite sides 59^a of a forked end at the upper extremity of an upright lever 59, said plates being adjustably fastened to the lever. (See Fig. 3.) This lever is fulcrumed on outwardly-extending brackets 60 of the framework, and to the lever is pivotally and adjustably connected a link 61, the latter being likewise connected to the upper portion of an actuating-lever 62, which lever is fulcrumed by a rock-shaft 63 within the framework. This actuating-lever is provided with a stud 64, on which is idly fitted a roller arranged to ride in a groove 65 (shown by dotted lines in Fig. 3) of a cam 66 on the counter-shaft 29, that drives the vertical shaft 26. The fulcrum-shaft or rock-shaft 63 has a stud against which acts a coiled spring 63^b, (shown by dotted lines in Fig. 3,) said spring being housed in a suitable fixed casing 63^c. This cam 60 through the lever 62 actuates the lever 59 and the roller therein to coil or wrap a binder around the filler, thereby completing the cigar-bunch and delivering the latter to a receiver 67, which is attached to the rolling-table at the delivery end of the apron 56.

In connection with the endless filler-trough I employ a gage 68, which is arranged longi-

tudinally of the table B on the opposite side of the filler-trough from the tobacco-receptacle b—that is to say, the filler-trough lies between the gage 68 and the receptacle, as shown by Fig. 2. This gage is arranged in close relation to the filler-trough at one side thereof and parallel therewith, and said gage may be mounted on the table B for adjustment to a limited extent and in a vertical direction. This gage is fashioned or constructed to partly overhang the open portion of the upper lead of the endless filler-trough, and said gage carries or supports a series of idle friction-rollers 69. (See Fig. 1, wherein a portion of the gage is broken away to show the overhanging portion thereof and some of the rollers of the series.) This series of rollers are raised above the trough and the table at a sufficient height to allow the easy introduction of the leaf-tobacco into the trough, and the rollers are free to turn when the tobacco is carried along by the trough, said rollers being rotated by the movement of the tobacco and offering practically no resistance to the advancement of the tobacco with the trough. The gage and the rollers serve in a measure to confine the tobacco within the open side and top of the trough; but the primary function of these parts is to determine the depth of the tobacco in the trough, and hence regulate the thickness of the filler and of the cigar-bunches. By adjusting the gage and the rollers relative to the trough the depth of the tobacco in the trough may be increased or diminished to secure the desired diameter of the cigar-filler and the bunches to be cut therefrom. The employment of the trough with self-opening side members in connection with the gage allows the machine to be worked by unskilled labor, and at the same time the machine will produce long-filler bunches of the desired shape and size, because the operator is only required to take the leaves of filler-tobacco from the receptacle b and to properly arrange them lengthwise in the trough below and against the gage which determines the depth of the filler or the diameter of the bunches when the filler is rolled in the binder. The end of the gage 68 terminates some distance short of the die-box, so that a portion of the filler-trough extends along the table beyond the gage before it discharges the filler into the die-box. To prevent the filler from rising above the trough after it leaves the gage and before entering the die-box, I employ the overhanging guide 70 and the gang of tucking devices shown by Figs. 1 and 2. The guide 70 is fastened to the table B to overhang the filler-trough, and it is disposed near one end of the gage. The tucking devices are embodied in the form of grooved wheels 71, 72, and 73, the same being supported to overhang the trough and to work partly in the latter, so as to confine the tobacco filler therein. The tucking-wheel 71 is mounted loosely on a bolt 74, attached to the upper portion of a vertical arm 75, which is

secured to the framework A for vertical adjustment thereon, as shown by Fig. 1. The other tucking-wheel 72 is similarly supported by a bolt 76 in the upper end of an arm 77, 5 fastened to the framework for vertical adjustment thereon. The remaining tucking-wheel 73 is smaller than the wheels 71 72 and is arranged in a position between the same; but this smaller intermediate wheel is loosely 10 mounted on a pin or bolt 78, which is secured to the middle portion of a horizontal bar 79. The end portions of this bar are fitted on the bolts 74 76, to be supported thereby, and by removing one of the bolts, as 76, the bar 79, 15 with the wheels 72 73, may be raised or turned on the bolt 74, so as to withdraw the wheels 72 73 from the trough for the purpose of obtaining access easily thereto in order to remove filler from the trough at the end of a 20 day's work, as is often desirable. These tucking-wheels do not exert any appreciable pressure on the filler of long-leaf tobacco; but they serve to hold or confine the filler in the trough after it leaves the gage and before it 25 enters the die-box. As a matter of fact, the filler or the bunch is not subjected to compression at any stage in the manufacture of the bunch, and hence I am able to produce long-filler bunches which are necessarily soft 30 and spongy and which do not have the filler condensed or compressed, which is liable to interfere with the free "drawing" of the completed cigar.

I will now proceed to describe the alternating ratchet mechanism, which imparts the advancing movement to the filler-trough in a manner to give the alternate long and short periods of movement thereto, so that the filler 35 will be cut by the knives E F to produce the embryo bunches in reversed order.

The bearing 5, which accommodates one end portion of the shaft 6, is provided with a rigid guide-block 80, (see Figs. 12 and 13,) 40 said guide-block being of any suitable angular form—as, for example, the square shape shown. On this guide-block is fitted a 45 shiftable pawl-lifter 81, which is provided with a slot of such shape and dimensions that the pawl-lifter is fitted to the guide-block in a 50 way to slide freely in a horizontal path for a limited distance. This pawl-lifter is in the form of a disk having a smooth peripheral surface, and against one face of the disk is arranged a single ratchet 82, the latter being 55 rigidly secured to an end portion of the shaft 6, which passes through the bearing 5, the guide-block 80, and the ratchet. The diameter of the pawl-lifter is equal to that of the ratchet, and in the normal position of the 60 pawl-lifter it is eccentric to the ratchet, as shown by Fig. 12. Said lifter is held in this eccentric position by a retractor device, herein shown as a spring 85, having a link 83 connected thereto, said link being pivoted to a 65 plate 83^a, attached to the pawl-lifter 81, said link being slidably fitted in a casing 84, which is secured fixedly to a part of the framework.

Within this casing is arranged the strong coiled retractor-spring 85, (indicated by dotted lines in Fig. 11,) one end of said spring being seated against a part of the casing, while the other end of the spring acts against the link to make it pull the pawl-lifter into the normal eccentric position. A pawl-carrier 87 is loosely fitted on the outer extremity of the 70 shaft 6, said carrier being in the form of a plate having lugs 88 88' at its ends and a curved flange 89, which overhangs and protects the ratchet 82. On one lug 88 of this pawl-carrier is mounted a feed-pawl 90, which 80 is movable with the carrier and is disposed opposite to the edges of the ratchet and the pawl-lifter, and when the pawl-lifter is in its eccentric position, as shown by Fig. 12, the nose of this pawl is adapted to engage with 85 one of the teeth of the ratchet; but when the pawl-carrier occupies the concentric relation to the ratchet, as shown by Fig. 13, the nose of the pawl engages with the edge of the lifter, so that the pawl cannot engage with the 90 ratchet temporarily. This pawl is pivotally mounted on the carrier and is normally pressed by a spring 91 to an active position.

92 designates an eccentric-carrying shaft, which is journaled in suitable bearings in the 95 lower part of the framework, and this shaft is equipped with a gear 93 and with a crank 94. (See Figs. 1 and 11.) The pinion 93 meshes with a spur-gear 95 on the sleeve 33, so that the shaft 92 is driven by the sleeve 100 when the machine is in gear. The crank 94 is secured to an end portion of the shaft 92, and in this crank is fitted an adjustable block 96, which carries a crank-pin 97, said block 96 being held and adjusted by a screw 98. 105 (See Fig. 11.) On this wrist-pin is fitted the lower end of a link 99, the upper end of which is pivoted at 100 to one lug 88' of the pawl-carrier 87, whereby the crank is adapted to reciprocate the link and impart rocking motion to the pawl-carrier 87, which in turn moves the pawl, so as to impart the desired movement to the ratchet, which in turn operates the shaft 6, that imparts the advancing movement to the filler-trough. When 115 the crank moves the pawl-carrier and the pawl the distance determined by the throw of said crank-pin and the pawl-lifter does not operate or remains silent, so as to have no influence on the pawl, then the ratchet is 120 turned an angular distance sufficient to impart the desired long period of movement to the filler-trough; but at alternate intervals to the periods of long successive movements the pawl is temporarily lifted from engagement 125 with the ratchet by the pawl-lifter, which is automatically actuated by the following devices: A cam-shaft 101 is journaled in bearings 102 at the lower part of the framework and to one side of the eccentric-shaft 92, and 130 these two shafts are intergeared through the gears 103 104 to make the cam-shaft rotate at half the speed of the eccentric-shaft 92. On this cam-shaft 101 is rigidly secured, with pro-

vision for longitudinal adjustment, a cam-sleeve 105, having a tapering or wedge-shaped cam portion 106 secured thereto, (see Figs. 11 and 14,) said sleeve and the raised plate 5 or portion thereon constituting the cam. An angular trip-lever 107 is fulcrumed on the framework in a position for one end thereof to ride on the cam, (see Fig. 11,) and this lever is provided with a shoulder 108, with 10 which engages the lower end of a trip-lever 109, the latter being disposed in a vertical position and fulcrumed at 110 on the framework, the upper end of said lever being pivoted at 111 to the pawl-lifter. The crank operates 15 the lever or link 99 to shift the pawl-carrier and make the pawl turn the ratchet a distance to impart the long period of movement to the filler-trough, the pawl-lifter remaining in its eccentric position, as has been described; 20 but on the next rotation of the shaft 92 and the crank the shaft 101 presents the projecting portion 106 of the cam 105 to the trip-lever 107, which is thereby raised and turns the lever 109, so as to pull on the pawl-lifter against the tension of the spring 85, and thus throw 25 the pawl-lifter against the pawl for the period that the high part 106 of the cam engages with the trip-lever. This has the effect of holding the pawl out of engagement with the 30 ratchet for a short period during the movement of the pawl-carrier under the action of the crank 96 and the link 99; but these parts actuate the carrier and the pawl in a manner for the latter to turn the ratchet a limited 35 distance, less than the first period of movement, and thus the ratchet mechanism is controlled and becomes effective to turn the shaft 6 and the filler-trough for the desired short period of movement. It will therefore be understood 40 that the ratchet mechanism operates automatically to give a long period of movement to the filler-trough, then a shorter period of movement to the trough, then a long period of movement, and so on indefinitely; but the filler-trough is not advanced continuously, but only intermittently, because the ratchet mechanism only becomes effective at 45 certain periods, owing to the action of the crank.

50 The operation in general respects may be described as follows: Motion is communicated to the shaft 32 by the pulley, and when the clutch 35 is thrown into gear with the sleeve or tubular shaft 33 the several mechanisms are driven in their proper order. One operator is stationed at the table B to supply the tobacco-leaves to the trough C, while a second operator is stationed at the rolling-table to place the binders on the rolling-apron. 55 The cutter devices and the plunger are operated so that the plunger makes two downward movements to one for the cutter devices, and the shaft 6 is rotated intermittently and for proper distances to impart the long and short periods of movement to the filler-trough. Assuming that the filler is supplied continuously to the intermittently-

moved trough and that the latter is advanced with a long period of its movement, the tobacco filler is forced through the die-box into position for the knives to act thereon. The slide, with the cross-head, is now depressed to force the knives through the tobacco filler, and thereby produce a filler conforming to the shape of the cigar which it is desired to produce. The knife E gives the shape to the head end of the filler, and the knife F makes the tuck end of the bunch-filler of a recess shape, thus leaving in the strip of the filler a V-shaped projection. The recess of the first filler is adapted to be closed together to form the tuck end of the first bunch in the process of completing said bunch by wrapping a binder thereon. The knives are now raised, and they remain in such raised 85 positions for a short period. The filler-trough is now moved by the alternating ratchet mechanism in a forward direction and with a short period of movement, and the filler is advanced through the die-box, so as to shove 90 the first or cut bunch-filler into the receptacle 50, while the projecting tuck end of the second filler, which is as yet unsevered from the continuous length of filler, is moved far enough into the die-box for the projecting tuck end to 95 lie close to the path of the head-knife E. The cutter devices do not descend at this short feed movement of the filler-trough; but the plunger does descend under the action of the triple cam, so that the first filler which 100 was deposited in the receptacle is carried downwardly by the plunger, and thereby deposited in the binder-wrapping mechanism in a position to receive the binder, which is wrapped on the filler to complete the bunch. 105 The filler-trough is now advanced again with a long period of movement, and the projecting tuck end of the second filler is carried beyond the die-box and into the receptacle for a distance equivalent to a bunch, and now the 110 cutter devices descend simultaneously with the plunger. At this downstroke of the cutter devices the head-knife E and the tuck-knife F cut through the continuous strip of filler, so as to produce the second and third fillers for the 115 second and third bunches, the second filler being formed with a projecting tuck end and a recessed head end, while the third filler is cut in the same shape as the first filler—that is to say, said third filler has a projecting head end and 120 a recessed tuck end. On the said long-period movement of the filler-trough the second bunch is placed in the receptacle 50 to be carried by the plunger to the binder-wrapping devices, which in their operation close the 125 recessed head end of the cut filler at the same time the binder is applied, while the third cut filler remains in the die-box. The plunger and the cutter devices now rise and the filler-trough moves forward with a short period of movement to carry the filler strip or 130 length along into the die-box, and thereby force the third cut filler into the receptacle, whereby the plunger descends, while the cut-

ter devices remain in their raised positions, thus causing the plunger to carry the third cut 5 filler into the binder-wrapping devices. These operations are repeated indefinitely in order to advance the length of filler, cut the same into fillers of proper shape and length, and apply the binders to the fillers; but it is to be noted that the bunches are reversed end for end when delivered from the binder-wrap- 10 ping mechanism, thus requiring the bunches to be rolled right and left, as has been previously explained.

I am aware that various modifications in the form, proportion, and size of the parts and 15 in the details of construction may be made by a skilled mechanic without departing from the spirit or sacrificing the advantages of my invention.

What I claim as new, and desire to secure 20 by Letters Patent, is—

1. In a machine of the class described, the combination of a cutter mechanism including head and tuck knives, means for advancing a tobacco filler for long and short distances 25 alternately to said cutter mechanism, and means for applying a binder to cut lengths of said filler.

2. In a machine of the class described, the combination of a cutter mechanism, a filler- 30 forming mechanism, and means for intermittently transferring a continuous length of tobacco filler for alternate long and short distances from said filler-forming mechanism to said cutter mechanism.

3. In a machine of the class described, the combination of a filler-forming mechanism, a cutter mechanism operable on a continuous 35 length of filler to produce therefrom short shaped fillers, and means for advancing a continuous length of filler in alternate short and long periods of movement to said cutter mechanism.

4. In a machine of the class described, the combination of a filler-forming mechanism, a 45 cutter mechanism operable on a continuous length of filler to produce therefrom short shaped lengths of fillers, and means for intermittently advancing a continuous length of filler, with alternate long and short periods of 50 movement, from the filler-forming mechanism to the cutter mechanism.

5. In a machine of the class described, the combination of a filler-forming mechanism, a die-box in line therewith, a reciprocable cutter-head, head and tuck knives movable with 55 said cutter-head and arranged to traverse the die-box, and means for intermittently actuating the filler-forming mechanism to advance a continuous length of filler for alternate long 60 and short distances into the path of said head and tuck knives.

6. In a machine of the class described, the combination of a die-box having shearing edges, a head-cutting knife arranged to traverse certain shearing edges of the die-box, a 65 tuck-cutting knife to traverse other shearing edges of the die-box, means for imparting re-

ciprocal movement to said knives, and means for feeding a length of tobacco into said die-box.

7. In a machine of the class described, the combination of a filler-forming mechanism, a cutter mechanism including reciprocatory knives, a binder-wrapping mechanism, a plunger arranged to transfer cut lengths of 75 filler from the cutter mechanism to the binder-wrapping mechanism, and means for actuating the cutter mechanism half as often as the plunger.

8. In a machine of the class described, the combination of a filler-forming mechanism, a set of reciprocatory cutter-knives to produce short shaped lengths of filler, a binder-wrapping mechanism, means for intermittently advancing a length of filler to the cutter-knives, a plunger to transfer cut lengths of 80 filler from beyond said knives to the binder-wrapping mechanism, means for reciprocating the plunger, and means for reciprocating the cutter-knives at each alternate stroke of 85 the plunger.

9. In a machine of the class described, a filler-forming mechanism comprising an endless sectional trough each section having one side self-opening, combined with means for closing said sides of the trough-sections, and cutter devices to sever a continuous length 90 of filler into short lengths of filler.

10. In a machine of the class described, a filler-forming mechanism including an endless trough comprising a series of hinged sections each having an outwardly-movable side, and means for closing the sides of the trough as the latter is moved, combined with a cutter mechanism, and means for imparting 105 movement to the trough intermittently.

11. In a machine of the class described, a filler-forming mechanism including endless chains, and a series of trough-sections attached to the links of the chains and each 110 having a self-opening pivoted side, combined with a cutter mechanism, means for intermittently moving the trough, and means for closing the pivoted sides of the trough.

12. In a machine of the class described, the combination of a movable filler-forming trough having one side thereof arranged to open automatically, and a stationary gage disposed adjacent to the non-opening side of 115 said trough and in overhanging relation to the cavity or chamber of said trough.

13. In a machine of the class described, the combination of a table, a movable filler-forming trough having one side thereof arranged to open into substantially flush relation to the 120 table, and a gage disposed adjacent to the non-opening side of the trough and having a member which overhangs the cavity of the trough, said gage being provided with anti-friction devices which face the trough.

14. In a machine of the class described, the combination of an endwise-movable sectional filler-trough, each section having one side self-opening, a filler-regulating gage disposed 130

adjacent to the non-opening side of the trough and leaving the trough free to be properly filled with leaf-tobacco, and rollers carried by said gage in position over the trough.

5 15. In a machine of the class described, the combination of an endwise-movable trough having self-opening members at one side, a gage disposed adjacent to the closed side of the trough, and a receptacle for a supply of 10 filler-tobacco adjacent to the open side of the trough.

15 16. In a machine of the class described, the combination of a table, an endwise-movable trough having one side composed of movable sections arranged to open in substantially flush relation to the top of the table, a gage adjacent to the closed side of the trough, and a receptacle for a supply of filler-tobacco near the open side of the trough.

20 17. In a machine of the class described, a cutter mechanism having a head-knife and a tuck-knife, combined with means for advancing a length of filler to said knives, and means for discharging cut lengths of filler 25 from beyond said knives.

30 18. In a machine of the class described, a cutter mechanism comprising a die-box, a head-knife, a tuck-knife, and means for moving the knives across said die-box, combined with means for advancing a filler to said die-box and into the path of the knives.

35 19. In a machine of the class described, the combination with a filler-trough, and means for moving the trough intermittently, of a cutter mechanism including a die-box and a set of head and tuck knives, said die-box being disposed adjacent to the delivery end of the trough to receive a filler therefrom.

40 20. In a machine of the class described, the combination with a filler-forming trough, of a die-box disposed in alinement with said trough and provided with a pick-up which extends into said trough, said die-box having knife-slots in angular relation in rear of 45 said pick-up, a head-knife adapted to traverse the die-box, a tuck-knife arranged to traverse the knife-slots in the die-box, and means for imparting reciprocating motion to said knives.

50 21. In a machine of the class described, a cutter mechanism having a die-box provided with cutting-edges, a head-knife arranged to traverse said edges of the box, and a tuck-cutter movable across the box, in combination with means for feeding a continuous 55 length of tobacco to said die-box.

22. In a machine of the class described, a cutter mechanism comprising a die-box having slots in its top and bottom and cutting 60 edges at the delivery end of said box, a tuck-knife arranged to play in the slots of the box, and a head-knife to traverse said cutting edges, combined with means for feeding a length of filler into said die-box.

65 23. In a machine of the class described, a filler-cutting mechanism including a head-knife having converging sides, and a tuck-

knife also having converging sides, the apices of both knives pointing in the same general direction, combined with a die-box, and means for advancing tobacco filler into the path of said knives.

24. In a machine for making soft-filler cigar-bunches, the combination of an endwise-movable sectional filler-trough each section 75 of which has one side self-opening, a cutter mechanism in line with the trough, a filler-regulating gage disposed adjacent to the non-opening side of the trough and leaving the trough free to be properly filled with leaf-tobacco, means for closing said self-opening sides of the trough, and filler-tucking devices co-operating with said trough and lying between the gage and the cutter mechanism, said tucking devices overhanging the trough 85 and spaced relatively thereto for confining the filler in the trough, without subjecting said filler to compression.

25. In a machine for making soft-filler cigar-bunches, the combination with a filler-trough, of a cutter mechanism in alinement 90 with the trough, a gage adjacent to the trough, and filler-tucking devices lying between the cutter mechanism and the gage and overhanging the trough, said tucking mechanism 95 being disposed in such relation to the cavity of the trough as to confine the tobacco filler therein without subjecting it to compression.

26. In a machine for making soft-filler cigar-bunches, the combination with a filler-trough, of a gang of grooved tucking-wheels 100 overhanging the trough and having their peripheral edges lying within the sides of the trough, said tucking-wheels being spaced uniformly in relation to the trough and in such 105 positions relatively thereto as to confine tobacco filler therein without subjecting it to compression.

27. In a machine of the class described, the combination of a filler-trough, a cutter mechanism in line with the trough, and a gang of 110 idle grooved tucking-wheels co-operating with said trough, certain of said tucking-wheels being adjustable to inoperative positions relative to the trough for exposing the latter.

28. In a machine of the class described, the combination of a filler-forming mechanism, a die-box, a slide carrying knives to traverse the die-box, a binder-wrapping mechanism, a plunger over said wrapping mechanism, 120 said die-box and the plunger being in line with the filler-forming mechanism and a double cam connected individually with the cutter-slide and the plunger to intermittently actuate the devices in due order.

29. In a machine of the class described, the combination with a filler-forming mechanism, of a reciprocating cutter mechanism, a binder-wrapping mechanism, a plunger over said wrapping mechanism, said cutter mechanism and the plunger being in line with the filler mechanism and a double cam connected through intermediate devices with the cutter mechanism and the plunger to actuate both

devices and to move the plunger twice to every stroke of the cutter mechanism.

30. In a machine of the class described, the combination of a cutter mechanism, a filler-forming mechanism, located in line with said cutter mechanism and an alternating ratchet mechanism operatively connected with said filler-forming mechanism to intermittently advance the same for alternately long and short distances.

31. In a machine of the class described, the combination with a filler-forming mechanism, and a driving-shaft therefor, of a ratchet on said shaft, a pawl-carrier having a pawl to engage said ratchet, means for actuating the pawl-carrier, and means to temporarily restrain the pawl from engagement with the ratchet at the alternate movements of pawl-carrier.

32. In a machine of the class described, the combination with a filler-forming mechanism, and a driving-shaft therefor, of a ratchet on said shaft, a rocking pawl-carrier equipped with a pawl to engage the ratchet, means for rocking the pawl-carrier, a cam, and means actuated by the cam to temporarily restrain the pawl from engagement with said ratchet during the alternate rocking movements of said carrier.

33. In a machine of the class described, the combination with a filler-forming mechanism, and a driving-shaft therefor, of a ratchet on said shaft, a pawl-carrier, a pawl on said carrier, a pawl-lifter normally out of operative

relation to said pawl, means for rocking the carrier, and a cam for controlling the relation of the pawl-lifter to said pawl.

34. In a machine of the class described, the combination with a filler-forming mechanism, and a driving-shaft therefor, of a ratchet on said shaft, a pawl-carrier equipped with a pawl, means to operate the pawl-carrier, a circular pawl-lifter, a retractor for holding the pawl-lifter normally in eccentric relation to the ratchet, a cam, and operative connections between the cam and the pawl-lifter to periodically move the latter into the path of the pawl.

35. In a machine of the class described, the combination with a filler-forming mechanism, and a driving-shaft therefor, of a ratchet on said shaft, a pawl-carrier equipped with a pawl, a shaft 92, a crank on said shaft 92, a link connecting said crank with said pawl-carrier, a cam-shaft 101, a cam on said shaft 101, a pawl-lifter in eccentric relation to the ratchet, a retractor for normally holding said pawl-lifter in such relation, and means connecting the cam and the pawl-lifter in such relation as to periodically interpose the latter in the path of the pawl.

In testimony whereof I have hereunto affixed my signature in the presence of two subscribing witnesses.
